CAP APPLYING APPARATUS

Harold W. Martin, Malverne, N. Y., assignor to
American Seal-Kap Corporation of Delaware,
Wilmington, Del., a corporation of Delaware

Original application June 23, 1941, Serial No.
399,280. Divided and this application August
26, 1941, Serial No. 408,291

8 Claims. (Cl. 226—88.1)

This invention relates to a machine for applying flexible skirted hood caps to milk bottles or the like and more particularly to a machine for applying and sealing caps of the above type having a pleated skirt coated in whole or in part with a thermoplastic adhesive which requires heat and pressure for sealing.

This application is a division of the co-pending application of Goodwin and Martin, Ser. 399,280, filed June 23, 1942, for Capping machine.

An object of the invention is to provide a mechanism of the above type having novel and improved details of construction and features of operation.

Another object is to provide a novel and improved mechanism of the above type having characteristics suited for commercial operation.

Another object is to provide novel and improved mechanism for applying a cap of the type above indicated to a bottle with the adhesive heat-softened for sealing.

Another object is to provide novel and improved mechanism for applying caps to bottle necks.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawings forming a part thereof in which a specific embodiment of the invention has been set forth for purposes of illustration.

In the drawings,

Fig. 1 is a top plan view of a cap applying and sealing mechanism embodying the present invention;

Fig. 2 is an end view, partly in section, of the cap applying mechanism;

Fig. 3 is a vertical section taken on the line 3—3 of Fig. 2;

Fig. 4 is a horizontal section taken on the line 4—4 of Fig. 3; and

Figs. 5, 6 and 7 are detail views illustrating successive steps in the capping and sealing operation.

In the following description and in the claims certain specific terms have been used for convenience in referring to various details of the invention. These terms, however, are to be given

as broad an interpretation as the state of the art will permit.

Referring to the drawings more in detail, the invention is shown in Fig. 1 as applied to a capping and sealing mechanism comprising magazine M having a plurality of tubes adapted to contain a plurality of stacks of nested caps for successive application to milk bottles, a picker mechanism P, which is adapted to pick successive caps from said stacks and supply them to a chute C along which the caps roll on the lower edges of their flared skirts in the path of radiant heat rays which are focused onto the adhesive carried by the skirt. From the chute 10 C the caps pass to a cap applying station S where they meet and are picked off by the advancing necks of milk bottles and are carried to a bank of rotating capping heads H which contract the skirts around the necks of the bottles and hold the same under sealing pressure.

The milk bottles are received by a suitable conveyor, passed through a filling device F of standard construction wherein they are filled with milk, thence past the cap applying station S and to the capping heads H above mentioned, after which they are redelivered to the conveyor. The filling station F and the capping heads H form a part of the standard filling and capping apparatus, the details of which form no part 25 of the present invention. The capping heads H may, for example, be of the form disclosed in a co-pending application, Goodwin and Martin, Ser. 383,752, for Capping head. The capping head is particularly designed to fold and seal 30 caps of the type referred to herein. It is to be understood, however, that other types of capping heads and other types of caps may be used if desired.

The magazine M, picker P and chute C, in accordance with the present invention, are formed 40 as a unit mounted on a suitable pedestal which may be positioned to supply caps with heat softened adhesive to the milk bottle heads as they advance from the filler F to the capping heads H on a standard filling and capping machine as above mentioned. These mechanisms are described more in detail in application 399,280 referred to above. This application relates 45 specifically to the capping station S.

The caps are discharged from the chute C into a vertical delivery chute 195, Fig. 2, wherein they drop onto a plate 196. The chute 195 may be secured between brackets 141 by a pivoted latch bar 193, and may be provided with a positioning lip 192 which rests on one of the brackets 141.

The chute 195 may thus be removed by lifting the latch bar 193 and sliding the chute from the frame formed by the ends of the brackets 141.

The plate 196 is mounted for rotation by means of a pin 197 mounted in a bracket 198 secured to the chute 195. A spring pressed ball 200, mounted in the bracket 198 bears against the upper surface of the rotating plate 196 and is adapted to engage recesses 201, Fig. 4, to frictionally position the plate 196 for the purpose to be described.

The plate 196 is provided with a plurality of arms 202 which are adapted to pass beneath the end of the chute 195 and to form stops on which the caps 20 rest in vertical position, as shown in Figs. 2 and 3. The arms 202 are separated by recesses 203 which are of a shape suited to receive the neck of an advancing milk bottle 204 so that the plate 196 is rotated by said bottle as it passes the cap applying station. In the embodiment shown in Fig. 4, each bottle rotates the plate 196 one-third of a complete revolution and positions the succeeding recess 203 to be engaged by the neck of the next succeeding bottle.

The delivery end of the chute 195 is provided with a control plate 210, which is slidably mounted on rods 211 held in a bracket 212 attached to the lower end of the chute 195 and pressed inwardly by springs 213. The plate 210 is preferably inclined slightly as shown, and is provided with an inner upturned lip 214 around which the cap slides as it is tipped from vertical to horizontal position by the advancing bottle. The plate 210 is positioned so that in normal operation there is a clearance between the plate and the bottle cap so that the cap does not engage the plate. However, if the cap is incorrectly positioned with respect to the advancing bottle neck a greater amount of clearance may be required to permit the cap to turn as indicated in Fig. 2 in response to movement of the bottle neck. Should this occur, any pressure exerted by the cap against the upturned flange 214 permits the plate 210 to slide horizontally so as to release the cap and permit the same to move freely onto the bottle neck. Furthermore, should the cap tend to tip up or slide from the bottle neck or otherwise be incorrectly positioned the flat plate 210 serves to limit such movement and to cause the cap to be seated on the bottle neck and to remain thereon as the bottle passes to the capping station. The cap thus seated is indicated at Fig. 5.

The bottle neck with the cap 20 loosely seated thereon now passes to the capping station which comprises a plurality of rotating capping heads 221, which are adapted to fold and compress the skirts of the caps and to seal the same.

The heads 221 may be of any standard type which are adapted to fold the skirts around the bottle necks and to hold the same under pressure until the adhesive sets. One type of capping head suitable for this purpose has been disclosed in the copending application of Carl W. Goodwin, Ser. No. 383,752.

In a standard filling and capping machine of the type above indicated platforms (not shown) elevate the bottles into the capping heads 221 which advance with the platforms and hold the folded skirts under pressure a sufficient length of time to permit the adhesive to set. The bottles are then lowered from the heads 221 as indicated in Fig. 7, leaving the caps completely sealed on the bottle neck. The bottles with the

caps thus positioned are then discharged onto the conveyor and are ready for delivery or shipment.

It is to be understood that the time of heating of the caps in the feed chute C and the sealing time of the capping head 221 may be selected in accordance with the particular adhesive being used so that the adhesive is first heated to the proper temperature for softening the same and the caps are later held under pressure in the sealing head a sufficient time to allow the adhesive to set and permanently secure the folds of the skirt.

The adhesive is cooled to a setting temperature substantially immediately by the cold milk bottle when the skirt is folded therearound in the capping head. At the speed of operation above mentioned by way of example, substantially flash heating and flash cooling is obtained. In this way, the adhesive-coated, skirted caps are applied to milk bottles and sealed thereon during the time usually required for applying discs to milk bottles in standard filling and capping machines. The cost of operation and the attention required in the dairy is accordingly not greatly increased, an important feature in the dairy industry where the margin of profit is decidedly small and the cost of capping must be kept to a minimum.

Although a specific embodiment of the invention has been shown for purposes of illustration, it is to be understood that various changes and modifications may be made therein as will be readily apparent to a person skilled in the art. Furthermore, the various features set forth above may be applied individually to other types of capping machines and for other uses and are not restricted to the specific combination disclosed. The invention is only to be limited in accordance with the scope of the following claims.

What is claimed is:

1. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, a rotatable member mounted below the end of said delivery chute and having blades spaced below said chute to engage and support a cap in vertical position as it falls to the discharge end of said chute, said member rotating with the advancing bottle necks to thereby tilt said caps from the vertical onto the bottle necks as the latter advance past said capping station.

2. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, a rotatable member mounted below the end of said delivery chute and having blades spaced below said chute to engage and support

a cap in vertical position as it falls to the discharge end of said chute, said rotatable member having recesses intermediate said blades to receive and be engaged by the advancing bottle necks to be rotated by the bottles in advancing past said capping station, said rotating blade and the end of said chute cooperating to tilt said cap from the vertical onto the bottle neck as the latter advances past said capping station.

3. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, means to hold said caps at the delivery end of said chute in vertical position for capping and a horizontal plate arranged at the discharge end of said chute and extending forwardly in the direction of travel of said bottles to overlie said cap as it is tilted from the vertical on the advancing bottle neck for guiding and positioning said caps onto said neck, said plate having an upturned lip at its forward edge about which the cap is tilted onto the bottle neck as the bottle advances past said capping station, and resilient means mounting said plate for limited horizontal parallel movement in the direction of movement of said bottle to provide clearance for the passage of an irregular or misplaced cap.

4. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, means to hold said caps at the delivery end of said chute in vertical position for capping and a horizontal plate arranged at the discharge end of said chute and extending forwardly in the direction of travel of said bottles to overlie said cap as it is tilted from the vertical on the advancing bottle neck for guiding and positioning said caps onto said neck, said plate having an upturned lip at its forward edge about which the cap is tilted onto the bottle neck as the bottle advances past said capping station and having an inclined lower surface adapted to position and set said cap on the bottle neck, and resilient means mounting said plate for limited horizontal parallel movement in the direction of movement of said bottles to provide clearance for the passage of an irregular or misplaced cap.

5. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, a rotatable member mounted below

the end of said delivery chute and having blades spaced below said chute to engage and support a cap in vertical position as it falls to the discharge end of said chute, said member rotating with the advancing bottle necks to thereby tilt said caps from the vertical onto the bottle necks as the latter advance past said capping station, and a horizontal plate arranged at the discharge end of said chute and extending in the direction of travel of said bottle, said plate having a lower surface adapted to overlie said cap for positioning the same on said bottle neck as the bottle advances past said capping station.

6. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, a rotatable member mounted below the end of said delivery chute and having blades spaced below said chute to engage and support a cap in vertical position as it falls to the discharge end of said chute, said member rotating with the advancing bottle necks to thereby tilt said caps from the vertical onto the bottle necks as the latter advance past said capping station, and a horizontal plate arranged at the discharge end of said chute and extending in the direction of travel of said bottle, said plate having a lower surface adapted to overlie said cap for positioning the same on said bottle neck as the bottle advances past said capping station, said plate being movable horizontally in response to pressure exerted by a misplaced or irregular cap.

7. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping station in substantially vertical position to be engaged by the advancing containers and seated on such containers by the horizontal movement thereof past said capping station, said mechanism comprising a delivery chute terminating at said station, a rotatable member mounted below the end of said delivery chute and having blades spaced below said chute to engage and support a cap in vertical position as it falls to the discharge end of said chute, said rotatable member having recesses intermediate said blades to receive and be engaged by the advancing bottle necks to be rotated by the bottles in advancing past said capping station, said rotating blade and the end of said chute cooperating to tilt said cap from the vertical onto the bottle neck as the latter advances past said capping station, and friction means holding said rotatable member in its respective cap receiving position whereby said plate is automatically advanced step by step by the progression of bottles passing said capping station.

8. In a machine for applying to containers and sealing thereon, partially preformed hood caps having foldable pleated skirts carrying a thermoplastic adhesive for securing the folds together, mechanism for supplying individual caps, with the adhesive softened for sealing, to a capping

station in substantially vertical position to be engaged by the advancing containers and seated on such containers by the horizontal movement thereof past said capping station, said mechanism comprising a delivery chute terminating at said station, a rotatable member mounted below the end of said delivery chute and having blades spaced below said chute to engage and support a cap in vertical position as it falls to the discharge end of said chute, said rotatable member having recesses intermediate said blades to receive and be engaged by the advancing bottle necks to be rotated by the bottles in advancing past said capping station, said rotating blade and

the end of said chute cooperating to tilt said cap from the vertical onto the bottle neck as the latter advances past said capping station and friction means holding said rotatable member in its respective cap receiving position whereby said plate is automatically advanced step by step by the progression of bottles passing said capping station, said friction means comprising spring pressed members engaging recesses in said member which are brought into alignment therewith when said member is at the successive-cap receiving position.

HAROLD W. MARTIN.
